(57) **CLAIM**

We claim the ornamental design for a vibration training apparatus, as shown and described.

DESCRIPTION

FIG. 1 shows a front view of the vibration training apparatus of the present invention;

FIG. 2 shows a side view of the vibration training apparatus of FIG. 1, the opposing side being the mirror image thereof;

FIG. 3 shows a rear view of the vibration training apparatus of FIG. 1;

FIG. 4 shows a perspective front view of the vibration training apparatus of FIG. 1; and,

FIG. 5 shows a perspective rear view of the vibration training apparatus of FIG. 1.

The broken lines illustrate environmental structure which forms no part of the claimed design.
